UNITED STATES PATENT OFFICE

SILAS J. HUDSON AND LAWRENCE M. GILLEY, OF AKRON, OHIO

DESIGN FOR AN ASH TRAY

Application filed March 25, 1931. Serial No. 39,242. Term of patent 14 years.

To all whom it may concern:

Be it known that we, SILAS J. HUDSON and LAWRENCE M. GILLEY, both citizens of the United States and residing at Akron, in the county of Summit and State of Ohio, have invented a new, original, and ornamental Design for an Ash Tray, of which the following is a specification, reference being had to the accompanying drawings, forming a part thereof.

In the drawings,

We claim:

The ornamental design for an ash tray as shown.

SILAS J. HUDSON.
LAWRENCE M. GILLEY.
